METHOD OF FORMING AND PREPARING TUBULAR COIL SUPPORTS

William F. Stahl, Kenilworth, Ill.

Application August 25, 1953, Serial No. 376,438

8 Claims. (Cl. 242—1)

This invention relates to coil supports and, more particularly, to a method of forming and preparing tubular coil supports. The invention is especially useful in connection with the making of coils used in the electronics industry such as, for example, tuning coils, transformer coils, etc. wherein wire is wound upon a tubular support that is then equipped with an adjustable core for tuning the coil.

Tubes generally are formed by laminating strips of material one upon another in a spiral winding operation. In this procedure a winding mandrel is provided and as the mandrel is rotated the strips of material are drawn thereabout in spiral form and usually a plurality of strips are wound one upon another to form a sturdy tubular coil. This method is generally adopted for the making of coils or coil supports used in the electronics industry. The reason laminated tubes are preferred is that they are relatively cheap and, therefore, the cost of the equipment in which they are used is considerably lessened. Where the tubes are used as coil supports and the coils are equipped with cores, which in many instances are movable so that the electric properties of the coil can be varied as required, it is essential that the tube be dimensionally accurate so that free movement of the tuning core may be realized.

In winding a coil, wire is drawn tightly about the tubular support. Since the wire is drawn taut, the tubular support is frequently distorted when the wire is drawn tightly thereabout. Even though it is readily possible to provide a tube that is dimensionally accurate in the winding operation set out above, still when the wire is drawn about the tube the tube becomes distorted and the advantages of the dimensional accuracy completely disappear.

In order to overcome the effects of the distortion that accompanies the wire winding operation, it is common for tubes to be ordered that are oversize and therefore even though the wire is drawn tightly about the tube and distorts the same by forcing portions thereof inwardly, the interior dimensions of the tubular support are still large enough to enable the insertion of cores and the movement of adjustable cores. While this practice enables electrical coils to be formed that function satisfactorily, the practice is nevertheless wasteful in that it requires a larger amount of wire to be used in the forming of each coil. The wire most frequently used is copper, and copper wire is quite expensive and the extra length of wire used in each coil over that which would be required if the tubular support maintained its dimensional accuracy during the winding operation, amounts to many thousands of dollars a year for each coil manufacturer.

It is accordingly an object of this invention to provide a method of forming and preparing a tubular coil support wherein the support remains undistorted after the wire coil has been wound thereon. Another object of the invention is to provide a coil-forming method in which a pair of matched man-

rels are employed, one being used to form a dimensionally accurate tubular coil support thereon and the other being used to support the tube while a wire coil is wound thereon, the dimensions of the matched mandrels being related so that after the wire coil has been wound upon the tubular support, the support remains dimensionally accurate. A further object of the invention is in the provision of a method of forming a coil wherein the tubular coil support remains dimensionally accurate during the coil winding operation, with the result that a support of precise size may be employed and a savings in the wire costs realized. Yet a further object is in the provision of a method as set out above, including the steps of winding a laminated tube upon a winding mandrel and thereafter supporting the tube on a support mandrel during the wire winding operation, the dimensions of the mandrels being matched in a relationship whereby a push fit is provided between the tube and the support mandrel. Additional objects and advantages will appear as the specification proceeds.

An embodiment of the invention is illustrated in the accompanying drawing, in which:

Fig. 1 is a perspective view of a tubular support equipped with end flanges; Fig. 2 is a broken perspective view of a winding mandrel and in which the step of winding a laminated tube is being carried out; Fig. 3 is a transverse sectional view of a winding mandrel with a tubular coil support thereon; Fig. 4 is a transverse sectional view of a tube after it has been removed from the winding mandrel; Fig. 5 is a transverse sectional view showing the tube being supported upon the support mandrel; Fig. 6 is a broken perspective view showing the step of winding a coil upon a supported tube; and Fig. 7 is a diagrammatic view showing a support and winding mandrel with specific dimensions applied thereto.

Fig. 2 will first be referred to, since it illustrates the first step of forming a laminated tube. In this figure, a tube-forming or winding mandrel is indicated by the numeral 10 and being drawn or wound about the mandrel 10 is a strip of material 11. While but a single strip 11 is illustrated in Fig. 2, it will be appreciated that any number of strips may be employed in forming the laminated tube. Actually, two or three strips are usually provided and one is wound upon another to form a multiple layer laminated tube. Any suitable material may be employed to provide the strip or strips 11 and customarily a fibrous material is employed. Specifically, the strip 11 may be formed of paper and it should be understood that the tube formed by this spiral winding operation may be subjected to later treatments such as impregnation to form a sturdy tubular support.

It is quite possible and now fairly common to form a spirally-wound laminated tube wherein the dimensions thereof are quite accurate. Preferably, then, the tube formed by the spiral winding step illustrated in Fig. 2 is a dimensionally accurate tube. Since spirally winding laminated tubes is old and well known in the art, a detailed description more elaborate than that set out above will not be given, since it is believed unnecessary to a complete understanding of the invention by those skilled in the art. Similarly, forming laminated tubes that are dimensionally accurate is also known in the art, and the precise apparatus and method employed for achieving this result should not then be set out in detail.

As shown in Fig. 3, after the laminated tube has been formed upon the mandrel 10, it is seen that the walls of the tube cling fairly close to the walls of the mandrel. Actually, there is a slight bowing outwardly of the walls of the tube but it is practically imperceptible while the tube is upon the mandrel 10. The bowing tendency, however, is more pronounced when the tube, which is designated by the numeral 12, is withdrawn from the

mandrel. It is seen in Fig. 4 that each of the side walls of the tube 12 bow outwardly slightly.

After the tube 12 has been formed upon the mandrel 10 it is withdrawn therefrom, which may be part of the winding operation, and it is then telescoped onto a support mandrel or coil-winding mandrel 13. The mandrel 13 is illustrated in Fig. 5. It is seen that when the tube 12 is telescoped onto the mandrel 13 that the side walls of the tube are straightened and the outward bowing thereof becomes very, very slight. It is important to choose the dimensions of the mandrel 13 carefully so that the tube 12 is properly supported thereon and distortion of the tube thereby eliminated during the coil-winding operation.

After the tube 12 is properly supported upon the mandrel 13, an elongated wire 14 is wound upon the tube 13 to form the electric coil. The wire 14 may be formed of any suitable material and usually the wire is copper. The coil may be wound in any suitable manner and, for example, the support mandrel 13 may be rotated to draw and wind the wire 14 thereabout. Coil-winding operations are well known in the art and a detailed description of such winding operations is believed unnecessary herein.

A completed support for a coil is illustrated in Fig. 1 and shows the tube 12 having been cut into an appropriate length to form the coil support 15. The support 15 is equipped at each end with an end or terminal flange 16. Usually the flanges 16 are secured in position upon the tube 12 or the sectioned coil support 15 prior to the wire-winding operation, although other procedures may be followed if desired.

It has been found that if the dimensions of the winding mandrel 10 and the support mandrel 13 are correlated properly, that the tube 12 when the wire coil is wound thereabout, will not be distorted and that the formed coil may readily have a metallic core inserted therein and, specifically, the coil may be equipped with a movable iron core that will enable the coil to be properly tuned to meet the requirements of the particular circuit arrangement with which it is used. In order that the core move freely within the tube, it is essential that the inner dimensions of the tube be accurate throughout the length thereof. If the inner dimensions are smaller at certain points along the tubular support, the core cannot be inserted and if a movable core is employed the core cannot be moved beyond the point of obstruction. Tuning, then, is seriously limited. On the other hand, if the inner dimensions of the support are too great, a movable core will not be adequately held by friction at any point of adjustment therein and chances are quite great that a coil, though properly tuned initially, will not remain tuned especially if the apparatus is subjected to any vibration which would cause movement of the adjusting core. It is fairly critical, then, that the dimensions of the tube used for the coil support remain quite accurate.

As has been brought out before, the customary practice has been to provide tubes 12 having greater dimensions than those actually required so that after the wire coil has been formed thereon the inner dimensions of the tubular support are still sufficient to enable a movable core to be employed therein and to be freely movable therein and not obstructed by areas of reduced dimensions. This is an extremely wasteful practice and it is therefore desirable to avoid the practice of ordering and using oversize tubes, if it is possible.

I have found that if the mandrel 13 used to support the tube 12 during the coil-winding operation is of such size that the tube 12 must be pushed onto the mandrel with a slight force during the telescoping operation, that the tube will then be properly supported and there will be no buckling and other distortion of the tube when the coil is wound thereon. Such a push fit can be obtained if the corners of the mandrel 13 snugly engage the corners of the tube 12, as is illustrated in Fig. 5. If this specific

arrangement is provided, it is apparent that the tube 12 will be supported at each corner portion and the corners thereof cannot be buckled inwardly when the wire is drawn tightly thereagainst. At the same time, the snug engagement between the corners of the mandrel and corners of the tube tend to flatten the side walls of the tube and minimize the bowing outwardly thereof.

A specific example of the dimensions employed in a matched set of winding and support mandrels is shown in Fig. 7. Specifically, in this example the winding mandrel 19 had side wall dimension of .515 inch while the support mandrel 13 had side wall dimensions of .505 inch. The matched mandrels 10 and 13 with the dimensions indicated in Fig. 7 were used in forming the laminated tube 12 and in thereafter supporting the tube 12 during the coil-winding operation. It was found that the tube 12 formed on the mandrel 10 having wall dimensions of .515 inch was snugly received upon the support mandrel 13 having side wall dimensions of .505 inch, and that the tube 12 had to be pushed onto the mandrel 13 with sufficient force to overcome the frictional resistance tending to prevent the telescoping movement of the tube 12 and mandrel 13 and a push fit between the two was thus provided.

When the coil was then wound upon the tube and the tube subsequently withdrawn from the mandrel 13, it was found that there was no distortion of the tube and a core was readily inserted thereinto. The matched mandrels were employed for a considerable period of time for winding tubular coil supports and for supporting the tubes during the coil-winding operation, and it was found that the results in wire saving costs alone amounted to about \$40,000 to \$50,000 a year for this one coil manufacturer. It is apparent, then, that in providing matched mandrels, one of which is used in the tube-winding operation and the other of which is used in the coil-winding operation as a support for the tube, that when the mandrels are matched dimensionally so that a push fit is necessitated between the tube and support mandrel when the same are telescoped together, that the coil may be formed upon this supported tube without the danger of distorting the walls of the tube and the inner dimensions thereof remain accurate. Thus it is not necessary to use oversize tubes as coil supports, and since many turns of wire are required to form each coil, the savings in costs are considerable.

While in the foregoing specification an embodiment of the invention has been set out in considerable detail for purposes of illustration, it will be apparent to those skilled in the art that considerable deviation from these details may be made without departing from the spirit and principles of the invention.

I claim:

1. In a method of forming a tubular core and preparing the same to have a material wound thereon, the steps of providing a tube-forming mandrel, winding strips of laminating material thereon to form a tube, providing a tube-supporting mandrel, removing the tube from said first-mentioned mandrel and telescoping the same about said supporting mandrel to support the same during the material-winding operation, said support mandrel having slightly smaller dimensions than said first-mentioned mandrel in a relation that necessitates said tube being pushed thereon in said telescoping operation.

2. In a method of forming a tubular core and preparing the same to have a material wound thereon, the steps of providing a tube-forming mandrel, forming a tube upon said mandrel, removing said tube after the formation thereof from said mandrel, providing a support mandrel having slightly smaller dimensions than said first-mentioned mandrel and being adapted to receive said tube thereon during the material-winding operation, and pushing said tube onto said support mandrel in preparation for having a material wound thereon, the dimensions of said support mandrel being related to the dimensions of said

tube and first-mentioned mandrel so that a push fit between the tube and support mandrel is provided.

3. In a method of forming a coil support, the steps of providing a tube-winding mandrel, spirally winding strips of material thereon to form a tube, removing said tube from said winding mandrel, providing a support mandrel, the dimensions of said support mandrel being slightly smaller than the dimensions of said winding mandrel and matched therewith to provide a frictional resistance between said support mandrel and said tube, when said tube is telescoped about the support mandrel, resulting in a push fit therebetween, and pushing said tube onto said support mandrel in preparation for having a material wound thereon.

4. The method of claim 3 in which said mandrels are polygonal in cross section.

5. The method of claim 4 wherein said polygonal mandrels are rectangular.

6. A method of forming a coil support, dimensionally accurate subsequent to a coil-winding operation wherein a wire coil is wound thereabout, comprising the steps of providing a pair of matched mandrels of polygonal cross section, one of which is a tube-winding mandrel and the other of which is a support mandrel having slightly smaller dimensions than said winding mandrel in a predetermined matched relation therewith, spirally winding strips of material about said winding mandrel to form a tube, said tube having slightly bowed side walls, removing said tube from said winding mandrel and pushing the same upon said support mandrel in preparation to having a wire coil

5
10
20

wound thereabout, said matched mandrels being so related dimensionally that when said tube is pushed onto said support mandrel the corner portions of the tube and support mandrel meet in a snug engagement, and winding a coil about the tube does not disturb the dimensional accuracy thereof.

7. The method of claim 6 wherein the additional step is provided of winding a wire core upon said tube when it is received on said support mandrel.

8. A method of forming a coil having a hollow polygonal core of predetermined internal dimensions, comprising the steps of spirally winding strips of material about a polygonal winding mandrel of preselected dimensions to form a hollow core, providing a polygonal support mandrel matched dimensionally with and to a slightly smaller size than the winding mandrel so that the corners of the core snugly engage the corners of the support mandrel when the two are telescoped while permitting the core faces to bow outwardly slightly, positioning said core upon said support mandrel, and winding a coil about said core.
